(57) **CLAIM**

The ornamental design for a garment tag, as shown and described.

DESCRIPTION

FIG. 1 is a perspective view of the garment tag in a closed position;

FIG. 2 is a perspective view of the garment tag in an open position;

FIG. 3 is a top plan view of the garment tag in an open position;

FIG. 4 is a bottom plan view of the garment tag in an open position;

FIG. 5 is a front elevational view of the garment tag in an open position, with the back elevational view, right side elevation view, and left side elevational view being identical;

FIG. 6 is a top plan view of the garment tag in a closed position;

FIG. 7 is a bottom plan view of the garment tag in a closed position; and,

FIG. 8 is a front elevational view of the garment tag in a closed position, with the back elevational view, right side elevation view, and left side elevational view being identical.

1 Claim, 8 Drawing Sheets
